TABLE LAMP

Howard C. Lindemann, Great Neck, N. Y.

Application June 14, 1952, Serial No. 20,205

Term of patent 7 years

(Cl. D48—20)

To all whom it may concern:

Be it known that I, Howard C. Lindemann, a citizen of the United States, residing in Great Neck, L. I., New York, have invented a new, original, and ornamental Design for a Table Lamp, of which the following is a specification, reference being had to the accompanying drawing, forming a part hereof.

Fig. 1 is a rear perspective view of a table lamp showing my new design;

Fig. 2 is a fragmentary front perspective view, the stand being omitted for convenience of illustration; and

Fig. 3 is a fragmentary side elevational view to a smaller scale, the stand being omitted for convenience of illustration.

I claim:

The ornamental design for a table lamp, as shown.

HOWARD C. LINDEMANN.
